COIN HANDLING APPARATUS

Paul H. Smyth, Jr., Evanston, Ill., assignor to
Rock-Ola Manufacturing Corporation, Chi-
cago, Ill., a corporation of Delaware

Application November 18, 1937, Serial No. 175,230

2 Claims. (Cl. 194—55)

This invention relates to vending machines for dispensing, for example, audible amusement, audible entertainment, or audible intelligence, as, for instance, a coin-controlled phonograph. The invention has more particular reference to coin handling apparatus for such vending machines.

An object of the invention is the provision of a novel and improved coin handling apparatus for coin-controlled machines.

Another object of the invention is the provision of a multi-coin handling apparatus that will cause the operation of the phonograph or other controlled machine a number of times determined by the denomination of the deposited coin.

A further object of the invention is the provision of a multi-coin handling apparatus which will predetermine the number of operations of the machine controlled thereby for each of a plurality of denominations of coins.

Another object of the invention is to provide such a multi-coin handling apparatus whereby the predetermined number of operations of the controlled machine will vary proportionately with the values of the deposited coins, so that, for example, twice as many operations are obtained for a dime as for a nickel, five times as many operations are obtained for a quarter as for a nickel, and so on.

Other objects of the invention will become apparent from the accompanying disclosure and include the novel constructions, combinations and arrangements of parts described and shown to disclose, by way of illustration, an embodiment of the invention which has been found suitable.

In the accompanying drawings:

Fig. 1 is a frontal perspective view shown with parts removed or broken away for clarity of a vending machine coin handling apparatus illustrative of an embodiment of the invention;

Fig. 2 is a rear end elevational view of the novel coin handling apparatus shown in Fig. 1;

Fig. 3 is a partial plan view of coin controlled actuating means found suitable for use in the novel coin handling apparatus;

Fig. 4 is an upright cross section through one of the coin controlled actuating units and is taken substantially along the lines 4—4 of Fig. 3;

Fig. 5 is a view similar to that shown in Fig. 4 and illustrating therewith the operation of the scavenger device;

Fig. 6 is a partial side view shown with parts in cross section and with parts broken away of one of the actuating devices of Fig. 3 to bring out certain details of assembly and construction;

Fig. 7 is a fragmentary cross section taken sub-

stantially along the lines 7—7 of Fig. 6 and shows the operation of the means for rejecting genuine coins while the coin is in the coin controlled actuating unit;

Fig. 8 is a fragmentary elevation of the scavenger device;

Fig. 9 is a fragmentary cross section taken substantially along the lines 9—9 of Fig. 8;

Fig. 10 is a view similar to Fig. 9 showing the actuation of the scavenger device;

Fig. 11 is a cross section taken substantially along the lines 11—11 of Fig. 2 and shows schematically a vending machine connected to the coin handling apparatus for control thereby;

Fig. 12 is a fragmentary elevational view showing certain details of the coin transferring mechanism and shows the coin release means for freeing that mechanism;

Fig. 13 is a side elevation of the novel coin handling apparatus with certain parts removed or broken away for the sake of clarity;

Fig. 14 is a fragmentary elevational view of one of the actuating units with parts shown in section and parts broken away to show portions of the coin path;

Fig. 15 is a fragmentary cross section taken substantially along the lines 15—15 of Fig. 13;

Fig. 16 is a fragmentary view similar to Fig. 13 and shows the operating means for the control means in locked position during the actuation of the operating means;

Fig. 17 is a view like Fig. 16 and shows that operating means in unlocked position; and

Fig. 18 is a fragmentary perspective view of the means for setting the operating means to operate the control means in accordance with the denomination of the coin employed in the actuating means.

By reference to the accompanying drawings and the detailed description to follow presently, it will be seen that the novel coin handling apparatus essentially comprises coin-controlled actuating means, control means and operating means actuatable by the coin-controlled actuating means for operating the control means a predetermined number of times depending upon the denomination of the coin employed in the coin handling apparatus.

In another aspect of the invention, as will presently be explained, the coin-controlled actuating means is of the fraud-resistant type whereby the predetermined number of operations of the control means is varied proportionately with the denominations of a plurality of genuine coins, but is not operated when spurious

or counterfeit coins are employed in the coin handling apparatus.

Briefly, then, upon operation of the coin-controlled actuating means, the operating means is actuated and causes the operation of the control means, for example, once for each deposited nickel, twice for each deposited dime and five times for each deposited quarter. It will be understood that each operation of the control means represents an operation of the machine controlled by the novel coin handling apparatus in a manner well known in this art.

The coin-controlled actuating means illustrated has been found suitable for use in the novel coin handling apparatus. It is of the fraud-resistant type and is adapted to receive coins of different denominations. As shown in Figs. 1, 2 and 3, the actuating means comprises a plurality of identical actuating units A, B and C, one such unit being provided for each desired coin denomination, or, by way of example, the unit A for nickels, the unit B for dimes and the unit C for quarters. Briefly, each of the actuating units A, B and C includes an outer plate D which cooperates with a frame member E pivoted thereon near an end thereof and with an intermediate plate F to provide communicating coin passages 21, 22 and 23 for genuine coins (Figs. 3 to 10 and 14). The intermediate plate F cooperates with a plate G at the side thereof opposite the plate D to provide a return passage 24 for spurious or counterfeit coins.

Those plates D, F and G of each actuating unit are mounted in a suitable frame including a front plate H having a plurality of intake or receiving apertures or slots 25 therein, each communicating with the upper end of one of the passages 21, and a plurality of return apertures or slots 26, each communicating with the lower end of the return passage 24 for returning rejected coins to positions outside of the coin handling apparatus. Slidably arranged between the plates D and F of each actuating unit is a reciprocable member or plunger I having a forward manually operable extension J extending through the front frame plate H, a rearward extension K extending through the back of the actuating unit, and a coin carrier 27 for receiving coins from the coin passage 23.

As shown in Figs. 11 and 13, reciprocable member I of each of the actuating units A, B and C is normally capable of movement over a relatively short distance in the direction from front to back, or inwardly of the actuating unit. Such movement is limited by a spring-urged dog or detent 28 pivotally mounted on the intermediate plate F and engageable with a shoulder 29 in the reciprocable member I for releasably dogging the reciprocable member against greater movement in that direction. That dog 28 is operable against the action of its spring by a coin in the coin carrier 27 during the limited movement of the reciprocable member I. Thus, when a coin is in the coin carrier 27, the reciprocable member I is movable against the action of a spring 31 inwardly of the actuating unit from a position wherein the coin carrier 27 is in communication with the coin passage 23 to a position wherein the coin carrier is in communication with an aperture or passage 32 in the bottom of the actuating unit. The coin in the coin carrier may thereupon drop into a suitable receptacle (not shown). To prevent the reciprocable member I from being returned to its initial position by the spring 31 before the reciprocable member has been moved

a full stroke as just described, a well known full stroke apparatus 33 may be operatively associated with the reciprocable member.

It will be understood that the actuating means described above per se forms no part of the present invention and is well known in the art. The invention is not therefore limited to the particular type of multiple-coin actuating means. It might be well, however, to point out by way of further explanation that when a genuine coin of proper denomination is inserted in one of the intake or receiving apertures 25 of the illustrated actuating means, the coin will roll or gravitate along the communicating passages 21, 22 and 23 into the coin carrier 27 whereby to permit manual movement of the reciprocable member I a full stroke inwardly of the corresponding actuating unit.

Preferably those passages 21, 22 and 23 are associated with various fraud resistant means for causing spurious or counterfeit coins to be rejected, that is, prevented from being delivered to the coin carrier 27. Instead, the rejected coins are delivered to the return passage 24 which directs them through the return aperture or slot 26 to a position outside of the actuating unit. The fraud resistant means for each of the actuating units A, B and C, as illustrated, includes a magnet 34 so arranged that a coin rolling along the passage 21 will enter the magnetic field of the magnet 34. The magnet 34 is of sufficient strength to stop magnetic slugs or other spurious coins of magnetic material in the passage 21.

In each illustrated actuating unit, as shown in Figs. 4, 5, 8, 11 and 13, scavenger means 35 for clearing the passage 21 of such magnetic slugs or coins or of other materials lodged in the passage is provided in the form of a pivoted scavenger arm 36 extending into the passage 21 and normally held in the upper portion of the passage by a spring 37. That scavenger arm 36 is movable about its pivot across the passage 21 by an end portion 38 of a pivoted arm 39. That end portion 38 is beveled to serve as a cam for engaging a roller or follower 41 on the pivoted frame E having a lower member 42 serving as the bottom or coin supporting and directing portion of the passage 21. The scavenger arm 36 is operable from the reciprocable member I by a connecting member or link 43 connecting the arm 39 with one end of a pivoted lever 44, the other end of which is provided with a cam surface 45 engageable with an actuating roller 46 on the reciprocable member I.

During the first portion of movement of the reciprocable member I inwardly of the actuating unit, the roller 46 engages the cam surface 45 and operates the lever 44. When the lever 44 is thus operated, the end portion 38 of the arm 39 cams the pivoted frame E outwardly about its pivot to open the passage 21, and swings the pivoted scavenger arm 36 downwardly across that passage 21. In that manner any obstruction in the passage is removed during each operation of the reciprocable member, and if the obstruction is a slug or other spurious coin, it is dropped through an entrance opening 47 of the return passage 24 and is directed thereby outside of the actuating unit through the return aperture 26. A spring 48 is provided for returning the pivoted frame E to its initial position when the cam surface 45 is disengaged by the roller 46.

The magnet 34, in cooperation with the inclined passage 21 and one or more suitably positioned anvil or buffer lugs 49 in the coin passage 75

22, and an entrance opening 51 communicating with the return passage 24, serves also to reject spurious or counterfeit coins which are not sufficiently magnetic to be stopped by the magnet. 5
5 The speed at which metal coins, whether spurious or genuine, roll along the inclined passage 21 will differ in accordance with what is termed herein the "electrical inductivity" of the particular metal or metals of which the coins are made. By "electrical inductivity" as used herein is meant that property of an electrical conductor moving through a magnetic field to have induced in the conductor an electric current having a magnetic effect opposing the motion producing the current. 10
10 Thus such coins rolling along the passage 21 are retarded in proportion to the electrical conductivity of the coin. That principle is utilized by arranging the entrance opening 51 with reference to the inner end of the passage 21 and 15 with reference to the lug or lugs 49 so that spurious coins are directed into the entrance opening 51 and returned through the passage 24 without ever reaching the coin carrier 27. 20

A spring or retarder 52 extends into the passage 21 ahead of the magnet 34 to prevent coins from being inserted in the receiving aperture 25 with such force that the retarding force caused by the magnet 34 will be insufficient to cause the selective rejection just described. If desired, an 25 aperture 53 may be provided between the passage 23 and the return passage 24 with a ledge 54 removed as at 55 toward the forward end of the aperture and extending upwardly from the bottom of the passage 23. A spring 56 may be arranged in the passage 23 in such a manner that if a spurious coin of a thickness greater than the thickness of a genuine coin should enter the passage 23, it will, in rolling therealong, be urged through the aperture 53 where the ledge 54 is removed and into the return passage 24.

Since in the present invention the control means designated generally by the reference character L is associated with the operating means indicated by the reference character M 45 actuatable by the coin-controlled actuating means, each of the actuating units A, B and C is provided with means for rejecting genuine coins while a coin is in the coin carrier 27. Such means assures sufficient time between subsequent 50 operations of each operable member I for operation of the control means L by its operating means M the number of times determined by the deposited coin.

That genuine coin rejector as illustrated in Figs. 55 7 and 11 comprises a relatively light strip 57 of metal for each actuating unit. The strip is pivoted intermediate its ends outside of the actuating unit and has an upper end bent or otherwise formed to provide a projection 58 registering with an aperture 59 in the outer plate 5 at the upper end of the coin passage 22. The lower end of each strip 57 is formed, for example, by bending to provide a projection 61 which extends into the coin passage 23 just above the normal position 65 of the coin carrier 27.

A coin entering the coin carrier 27 from the passage 23 engages the projection 61 and swings the pivoted strip 57 against the action of gravity to move the projection 58 through the aperture 59 into the passage 22. The strip 57 is held in that position by the coin in the carrier 27 until the coin is moved inwardly out of engagement with the projection 61 whereupon gravity returns the strip to its initial position. While 70 the projection 58 is in the passage 22, a coin

moving from the passage 21 into the passage 22 will strike the projection 58 and will thereby be deflected through the entrance opening 51 into the return passage 24.

The control means L and its operating means M are shown best in Figs. 11, 13 and 15 to 18 and are mounted on a suitable frame P. That frame may be cast or otherwise formed with angularly arranged plates 62 and 63, a strip 64 extending from the lower end of the plate 63 at the 10 margin thereof opposite the plate 62 and in the same direction from the plate 63 as does the plate 62, and a ledge 65 extending transversely along the face of the plate 62 opposite that from which the strip 64 projects. The plate 63 is provided 15 with a plurality of apertures 66 therein above the ledge 65 and spaced transversely along the plate to receive therein the respective rearward extensions K of the reciprocable members I when the frame is secured to the actuating units in 20 assembled relationship. Over the apertures 66 the plate 63 has a plurality of pairs of spaced lugs 67, 68 and 69 projecting from the same face of the plate as that from which the strip 64 projects. 25

That frame P is assembled at the rear ends of the actuating units A, B and C with the ledge 65 under the actuating units and with one rearward extension K extending through each aperture 66 in the plate 63. Screws or other suitable means 71 are employed to secure the frame in that position.

Instead of employing control means for each coin denomination and for actuation by the coins themselves, the control means L of the present 35 invention is common to all of the operable coin denominations and is operable by the operating means M a predetermined number of times, depending upon the denomination of the coin which is employed to render one of the reciprocable 40 members I operable.

The control means L is shown as a pair of normally open electrical contacts 72 carried in make-and-break relationship at the corresponding ends of a pair of resilient conductor strips 73 and 74. 45 Those contact-carrying strips are insulated from one another and are mounted as at 75 on the plate 62. The strip 74 is provided with a depending member 76 of insulating material to facilitate flexing the strip against its resiliency 50 in a contact-making direction.

As already mentioned, that control means L may be employed to control various machines. For example, it is illustrated for controlling a well known multi-record phonograph, shown diagrammatically at R in Fig. 11. Briefly, such a phonograph comprises an operating circuit including an electric motor 77, a source 78 of electrical energy, and a switch 79 electrically connected in circuit with the energy source 78 and the motor 77 for controlling the latter. Switch-operating means are provided in the phonograph for closing the switch 79 and maintaining it in the closed position until the motor 77 has operated the phonograph through a predetermined 65 number of complete playing cycles.

In other words, the operating means for the switch 79 is a sort of playing cycle accumulator and dispenser and comprises a rotatable ratchet 81 having a pin 82 thereon which normally holds the switch 79 open, a spring 81' for yieldably holding the ratchet 81 in a switch-open position, a spring-urged pawl 83 and a solenoid 84 for indexing the ratchet 81 in a switch-releasing or closing direction, a spring-held escapement pawl 75

83' permitting operation of the ratchet by the pawl 83 and operable to permit the spring 81' to return the ratchet with a step by step movement in a switch opening direction, and a movable phonograph member 85 movable at the end of each playing cycle for operating the pawl 83' to cause the indexing of the ratchet 81 in a switch-opening direction. The solenoid 84 is electrically connected in a circuit having a source 86 of electrical energy and including the control means L.

Thus, the first time the control contacts 72 are closed, the pawl 83 and solenoid 84 index the ratchet 81 to move the pin 82 in a direction to release the switch 79, causing it to close. If without further operation of the control means L the phonograph is permitted to play through its cycle, the movable member 85, the escapement pawl 83', and the spring 81' at the end of that cycle, will operate the ratchet 81 to return the pin 82 to its initial position, thereby opening the switch 79 and de-energizing the phonograph motor 77.

If the control means L is operated a plurality of times, the pin 82 rotating with the ratchet 81 is removed from the switch 79 one tooth or step for each operation of the control means L, and each movement of the pin or each operation of the control means corresponds to a cycle accumulated by the operating means for the switch 79. At the end of each cycle the member 85 returns the ratchet 81, and hence the pin 82, one step in a switch-opening direction so that at the end of the number of cycles corresponding to those accumulated by the switch-operating means, the pin 82 will open the switch 79 and will de-energize the phonograph motor 77.

The operating means M for the control means L comprises a ratchet or other rotatable member 81 rotatably carried at the outer end of a bolt or post 88 extending laterally from the plate 62. The ratchet 81 is provided with teeth or other projections 90 about its periphery for energizing a combined follower and detent member 91 at the outer end of an arm 92 pivoted as at 93 on the plate 62. That member 91 is yieldably held in such engagement with the ratchet teeth 88 by the resilient contact-carrying strip 74 acting through the depending member 76. As the ratchet is rotated, each tooth cams the follower and detent member 91 in a direction to close the contacts 72 against the resiliency of the contact-carrying strips 73 and 74. The resiliency of those contact-carrying strips returns the contacts to their open position after each such camming action and returns the member 91 to a position to resist rotation of the ratchet in a counter-clockwise direction, as viewed in Fig. 11.

Rotatably mounted on the post 88 between the ratchet 81 and the plate 62 is a member 94 of, for example, sector-shape. That sector-shaped member extends outwardly from the post beyond the periphery of the ratchet and carries a pawl 95 pivoted as at 96 at the outer end thereof and yieldably held in engagement with the ratchet teeth by a spring 97. A stud or projection 99 on the plate 62 is engageable by the sector-shaped member 94 to limit rotation thereof and the pawl 95 about the post 88 in one direction. By means of an operating stud or projection 99 at the lower end of the sector-shaped member 94, that member may be swung about the post 88 out of engagement with the limit stud 98 in a counter-clockwise direction as viewed in Fig. 11.

During such movement of the member 94, the pawl 95 slidably engages the ratchet 81. The op-

erating stud 99 may be utilized to swing the sector-shaped member 94 and the pawl 95 in opposite direction to cause the pawl to drive the ratchet 81. When the ratchet 81 is so operated, its teeth operate the combined follower and detent member 91 to close and open the switch contacts 72 once for each ratchet tooth engaging the member 91.

A link 101 is provided with an elongated aperture 102 at an end thereof for slidable and pivotal connection with the operating stud 99. That link 101 cooperates with a rockable member 103 which is actuatable by the reciprocable members I for operating the ratchet 81 to cause it to close the contacts 72 a number of times determined by the 15 denomination of the coin employed to release one of the reciprocable members.

That rockable member 103 is cast or otherwise suitably formed with a pair of spaced bearings 104 pivotally secured on a pin 105 extending transversely of the frame P and secured at opposite ends in the outer ends of the strip 64 and the plate 62. The bearings 104 are respectively integral with arms or other projections 106 and 107 extending radially outwardly from the bearings and offset from one another about the axis of the bearings. Between those arms 106 and 107 is an arm or projection 108 which is connected to the arm 106 by a web portion 109 and to the arm 107 by a web portion 111. The arm 108 is offset from the arm 106 in the same direction about the axis of the bearings 104 as is the arm 107 but for a lesser distance. Each rearward extension K of the reciprocable members I carries a roller or suitable projection 112. Extending forwardly from the web portion 111 is an arm or projection 113 with its forward end pivotally connected as at 114 with the link 101.

The arms 106, 108 and 107 are so spaced along the pin 105 that each is engageable by one of the rollers 112 when the corresponding reciprocable member I is operated. Due to the offsetting, those arms are engageable by the rollers 112 at relatively different positions of the rollers during the rearward movements of the respective reciprocable members I. Thus, each reciprocable member I is adapted to rotate the rockable member 103 against the action of a spring 115 through a different angle. During the rearward or inward movement of any one of the reciprocable members I, the corresponding roller 112 engages one of the arms 106, 108 or 107 and rotates the rockable member 103 through an angle depending upon the particular reciprocable member which is operated. The direction of that rotation of the rockable member 103 is such as to cause the arm 113 to move the link 101 upwardly. The elongated aperture 102 permits some lost motion of the link 101 when the spring 115 returns the rockable member 103 to its initial position.

That upward movement of the link 101 actuates the operating stud 99 to energize the means for operating the contact 72. In other words, the rotation of the rockable member 103 by one of the rollers 112 operates the operating stud 99 against the action of a spring 116 and thereby rotates the sector-shaped member 94 about the post 88 in the direction in which the pawl 95 slides about the teeth of the ratchet 81. The pawl 95 is caused to slide about a predetermined number of the teeth of the ratchet 81 by each reciprocable member I and, due to the offset of the arms 106, 108 and 107, the number of ratchet teeth about which the pawl 95 slides depends upon which of the reciprocable members I is 75

operated or, stated slightly differently, upon the denomination of the coin which releases one of the reciprocable members I.

The spring 116 is thus energized and is adapted to move the pawl 95 in the opposite direction and to return it to its initial position whereby to drive the ratchet 87 and thereby to operate the contacts 72 a number of times equal to the number of ratchet teeth about which the pawl 95 was caused to slide by the operation of the reciprocable member I. In other words, the contacts 72 are operated a predetermined number of times for each coin and a different number of times for each denomination of coin which releases one of the reciprocable members.

As already explained, the spring 116 is adapted to return the pawl 95 to its initial position, i. e., to the position at which the sector-shaped member 94 carrying the pawl 95 engages the stop 20 or limit stud 98. A dash pot 117 secured as at 118 to the plate 62 is provided with a reciprocable connecting member 119 depending from the dash pot piston or plunger and having an aperture 121 in the lower end of the connecting member for receiving therein the operating stud 99. That aperture 121 is elongated transversely of the connecting member 119 to accommodate the lateral displacement therein of the operating stud 99 during its pivotal movement about the post 88. The dash pot 117 constitutes means for controlling the velocity of the sector-shaped member carrying the pawl 95 while the pawl is driving the ratchet 87. Such control of the velocity of the sector-shaped member assures a positive closing of the contacts 72 for each ratchet tooth engaging the member 91 while the ratchet is being driven by the pawl 95. Thus, the spring 116 and the dash pot 117 cooperate to control the frequency of the closing and opening of the contacts 72.

In order to prevent operation of the contacts 72 by the ratchet 87 until the spring 116 is energized, the ratchet is positively locked against rotation during the operation of the rockable member 103 and is automatically released when the spring 116 is energized. Suitable means for accomplishing that result comprises an arm 122 pivoted at one end as at 123 adjacent the dash pot 117 on the plate 62 and having at its other end a shoulder 124 and a laterally projecting pin 125. The arm 122 extends downwardly from its pivot 123 and is of sufficient length that the shoulder 124 will move to and from a position over the detent member 91. When the shoulder 55 is over the detent member 91, that member is held in locking engagement with the teeth of the ratchet 87. The movement of the arm 122 out of locking engagement with the detent member 91 is limited by a suitable stop 125. Thus, the detent member is operable by the arm 122 for releasably locking the ratchet 87 in inoperative position while the pawl 95 is being moved to driving position.

That arm 122 is normally urged toward locking position by a spring 126 but is normally held out of engagement with the detent member 91 by an arm 127 of a lever 128 which is pivotally mounted to swing about the post 88 at the side of the ratchet 87 opposite the sector-shaped member 94. The arm 127 extends radially outwardly from the post 88 and extends between the pin 125 on the lower end of the arm 122 and the detent member 91. The lever 128 has an operating arm 129 which extends radially outwardly from the post 88 at an angle to the arm

127 and which has a laterally projecting pin 131 thereon. That operating arm 129 is connected to the rockable member 103 by a link 132 having at one end an elongated aperture 133 therein for slidable and pivotal connection with the pin 131 and pivoted at its other end on the pivot 114 of the arm 113.

The link 132 normally engages the pin 131 in the upper end of the elongated aperture 133 and serves to hold the lever 128 in such a position that the arm 127 engages the pin 125 and holds the arm 122 against the action of its spring 126 out of engagement with the detent member 91. A spring 134 between the operating arm 129 and a suitable anchorage on the plate 62 15 normally urges the lever 128 in a direction to cause the arm 127 to release the locking arm 122 so that its spring 126 can move it toward locking engagement with the detent member 91.

Thus, when the rockable member 103 commences to move in the direction for energizing the spring 116, the link 132 is moved sufficiently to permit the spring 134 to rotate the lever 128 and to move its arm 127 from engagement with the pin 125 and into engagement with the detent member 91. That movement of the arm 127 releases the locking arm 122 which is thereupon swung by its spring 126 into locking engagement with the detent member 91.

The detent member 91 is releasably held in 30 locking engagement with the teeth of the ratchet 87 by the spring-urged arm 122 while the rockable member 103 is positioning the pawl 95 for driving the ratchet 87, the elongated aperture 133 permitting sufficient lost motion of the link 35 132 while that is being accomplished. During the return movement of the rockable member 103 by the spring 115, the elongated aperture 133 permits some lost motion of the link 132 relative to the pin 131 until the rockable member 40 is substantially at its initial position whereupon the link 132 engages the pin 131 at the upper end of the elongated aperture and moves it against the action of the spring 134 to rotate the lever 128 in a direction to cause its arm 127 45 to remove the arm 122 from locking engagement with the detent member 91. Thus, the ratchet 87 is released and can be rotated by the spring actuated pawl 95 and controlled by the dash pot 117 to close and open the contacts 72 as already described.

Each pair of spaced lugs 67, 68 and 69 of the frame P has pivoted therebetween by a pin 135 a pawl or other suitable member 136. The members 136 extend rearwardly into engagement on 55 rollers 112 and to respectively overlying relationship with a plurality of forwardly extending arcuate strips 137, 138 and 139 secured on the rockable member 103 in any suitable manner. Each of those arcuate strips is provided with a slot 60 therein which in the respective strips is designated by the reference characters 141, 142 and 143 and which is adapted to receive therein a locking member 144 provided at the rear end of each pawl 136 for preventing rotation of 65 the rockable member 103 beyond the position to which it is rotated by the actuated reciprocable member I. The slots 141, 142 and 143 in the respective strips 137, 138 and 139 are successively rearwardly offset from the normal positions 70 of the locking members 144 and from one another for distances respectively corresponding to those between the locking members in normal position and the arms 106, 108 and 107 in normal positions.

Those locking members 144 are of any suitable construction and are made as shown, for example, in Fig. 11 by bending the rear ends of the pawls 136 in alignment transversely of the main bodies thereof and if desired, suitably securing a metal plate to each of the bent ends. Rearwardly beyond the ends of the spaced lugs 67, 68 and 69 each pawl 136 is provided with a downwardly facing cam surface or edge 145 for engagement by the underlying roller 112. The configuration of each of the cam surfaces 145 is such that the pawl 136 swings downwardly by gravity during rearward movements of the engaged rollers 112 and upwardly when the roller 15 engages the cam surface during the forward movements of the roller.

Thus, one of the pawls 136 gravitates about its pivot to move its locking member 144 to locking engagement in the slots 141, 142 or 143 when the corresponding reciprocable member I rotates the rockable member 103 sufficiently to cause the pawl 95 to be positioned for rotating the ratchet 87 to operate the contacts 72 a number of times depending upon which of the reciprocable members I is actuated. The locking member remains in that locking position to hold the rockable member 103 in that position until the roller 112, following the return of the reciprocable member I by the spring 31, cams the pawl upwardly about its pivot to move the locking member out of engagement in the slot. When the locking member has thus released the rockable member 103, the spring 115 returns the rockable member to its initial position causing the link 132 to operate the lever 128 whereby to move the locking member 122 out of locking engagement with the detent member 91, thus releasing the ratchet 87. When the ratchet is thus released, the spring 116 operates the sector-shaped member 94 to cause the pawl 95 to drive the ratchet and thereby to operate the contacts 72.

In operation, any one of the normally locked reciprocable members I may be released by inserting a coin of the proper denomination in the appropriate aperture 25. The inserted coin will by gravity move along the passages 21, 22 and 23 into the coin carrier 27 as indicated in Figs. 11 and 14 whereupon the reciprocable members I may be moved inwardly by pressure applied 50 against the end of the manually operable extension J.

Such movement of the reciprocable member I moves the corresponding extension K in a direction to rotate the rockable member 103 in a clockwise direction as viewed in Fig. 13 about its pivot 105 whereby to cause the arm 113 to move the links 101 and 132 upwardly. The upward movement of the link 132 is an idling movement relative to the pin 131 and permits the spring 134 to swing the lever 128 from the position shown in Fig. 13 to that shown in Fig. 16, thus permitting the spring 126 to move the arm 122 into locking engagement with the detent member 91 for preventing rotation of the ratchet 87.

The upward movement of the link 101 rotates the sector-shaped member 94 out of engagement with the stop pin 98 in a clockwise direction as viewed in Fig. 13 to move the pawl 95 slidingly about a number of teeth of the ratchet 87 determined by which of the reciprocable members I was operated to rotate the rockable member 103 or, in other words, determined by the denomination of the coin employed to release the means for actuating the rockable member 103. For example, if a five-cent piece or nickel is inserted

in the nickel aperture 25 (Fig. 1) the rearward extension K of the reciprocable member I corresponding to that nickel aperture will engage the arm 107 of the rockable member 103 and, due to the offsetting arrangement of that arm, will rotate the member 103 sufficiently to move the pawl 95 one tooth in a clockwise direction as viewed in Fig. 13 from its zero or initial position. The rearward extension K of the reciprocable member I corresponding to the dime or ten-cent piece slot 25 will, when operated, engage the arm 108 of the rockable member 103 to rotate that member sufficiently to rotate the pawl 95 about the ratchet 87 two teeth in a clockwise direction as viewed in Fig. 13 from the initial position of the pawl. Likewise the reciprocable member I corresponding to the twenty-five-cent or quarter aperture 25 is operable to engage the arm 106 of the rockable member 103 and to rotate that member sufficiently to move the pawl 95 five ratchet teeth 20 away from its initial position. In other words, the number of ratchet teeth about which the pawl 95 is moved by the rockable member 103 and its associated apparatus is predetermined for each reciprocable member I and varies proportionally with the values of the coins adapted to release those reciprocable members.

As any rearward extension K is operated to rotate the rockable member 103 in the manner just described, the roller 112 engaged by the cam surface 145 permits the arm 136 to swing downwardly to move the latching member 144 into latching engagement with the slot 141, 142 or 143 of the arcuate strip 137, 138 or 139 releasably latching the rockable member 103 in its rotated position against the action of the spring 115. The rockable member is automatically released by the roller 112 engaging the cam surface 145 and camming the arm 136 upwardly to remove the latching member 144 out of the slot 141, 142 or 143 during the return movement of the reciprocable member I, thus permitting the spring 115 to drive the rockable member 103 toward its initial position. During that return rotation of the rockable member 103 to its initial position, the arm 113 lowers the links 101 and 132, the elongated aperture 133 in the link 132 permitting idling movement of the link 132 relative to the pin 131 until just before the rockable member reaches its initial position. The link 132 thereupon engages the pin 131 and rotates the lever 128 to move the arm 122 out of latching engagement with the detent 91. Thereafter the spring 116 returns the sector-shaped member 94 and the pawl 95 to their initial positions, causing the pawl 95 to rotate the ratchet through an arc measured or determined by the number of ratchet teeth about which the pawl was previously moved when the rockable member was rotated by the reciprocable member I as already described. During such return movement of the pawl 95, the ratchet teeth will engage the follower and detent member 91 and will operate it a number of times equal to the number of teeth about which the pawl was displaced whereby to close and open the electrical contacts 72 the same number of times. Each closing of the contacts as already described will cause the solenoid and pawl 83 to rotate the ratchet 81 the distance between succeeding teeth whereby to accumulate the operation cycle of the phonograph or other device controlled by the novel coin handling apparatus. The control device is thus started and at the end of each operating cycle will operate the escapement pawl 83' to rotate the ratchet 81' in the opposite direction 75

the distance between succeeding ratchet teeth whereby to dispense the accumulated operating cycles.

While the invention has been disclosed in connection with a specific embodiment, it will be understood that the invention is not limited to the details employed herein by way of illustration but is capable of considerable variation and modification within the spirit and scope of the appended claims.

Having thus described the invention, what I claim as new and desire to cover by Letters Patent is:

1. In coin handling apparatus of the class controllable by coins of any of a plurality of different denominations, control means for controlling an operable device, means including a rotatable member for operating said control means, means rotatable in one direction in sliding engagement with said rotatable member and in the opposite direction in driving engagement with said rotatable member, rockable means for rotating the last said means a plurality of different distances in the first said direction, normally latched coin releasable means for rotating said rockable member for any of said distances, means for releasably locking said rockable member after it has been rotated the desired distance, means for releasing said rockable member and for returning it to its initial position upon return of said releasable means to latched position, and means for thereafter operating the means for driving said rotatable member to operate said control means.
2. The combination with a plurality of manually actuatable members each releasable by a coin of given denomination, of a rockable member provided with spring means for returning the same to normal position and provided with means each engageable by one of said actuatable members whereby the rockable member is operable through a predetermined arc peculiar to the denomination of the releasing coin, a rotatable ratchet, a pawl member co-axially mounted with respect to said ratchet, a swingable contact operating member having a portion arranged for contact with the teeth of the ratchet and operable by the latter during operation of the ratchet in one direction, a latch arranged for swinging movement from and to a position of cooperative engagement with said tooth contacting portion of said contact operating member for releasably locking the ratchet against rotation, and a pair of links each operable by said rockable member, one of said links being operatively connected to said pawl for retracting the same arcuately along the number of teeth of the ratchet predetermined by the arcuate movement of said rockable member and said other link being operatively connected to said latch and arranged to swing the same out of engagement with said contact operating member upon return of said rockable member to normal position.

PAUL H. SMYTH, JR. 30
